UNITED STATES PATENT OFFICE

140,336

DESIGN FOR A COLLAPSIBLE MUSIC STAND

Frank Gambe, Brooklyn, N. Y.

Application November 30, 1944, Serial No. 116,626

Term of patent 14 years

(Cl. D33—10)

To all whom it may concern:

Be it known that I, Frank Gambe, a citizen of the United States, residing at Brooklyn, in the county of Kings and State of New York, have invented a new, original, and ornamental Design for a Collapsible Music Stand, of which the following is a specification, reference being had to the accompanying drawings, forming a part thereof.

In the drawings:

Fig. 2 is a side elevational view thereof;

Fig. 3 is a front elevational view thereof; and
Fig. 4 is a top plan view.

I claim:

The ornamental design for a collapsible music stand, as shown.

FRANK GAMBE.
